UNITED STATES PATENT OFFICE

FREDERICK A. KAPPELMANN, OF BROOKLYN, NEW YORK

COMPOSITION-FLOOR STRIP

Application filed March 5, 1927. Serial No. 173,129.

This invention relates broadly to protecting strips for composition floors.

One of the objects of this invention is to provide a strip adapted to be mounted between the adjoining faces of the sections comprising a composition flooring, such as concrete, terrazzo, and, in fact, a floor made of any of the usual floor compositions.

Another object of this invention is to provide a strip of this nature characterized by the fact that it is securely attached to one section of the flooring while adapted to permit transverse movement thereof with respect to the adjoining section.

A still further object of this invention is to provide a protecting strip for composition flooring which is adapted to be embedded between the sections which comprise the flooring in such a manner that it is rigidly secured to the flooring on one side of the strip and permitted guided movement with respect to the flooring on the other side thereof.

These and many other objects are successfully sought by means of this invention.

This invention resides substantially in the construction, combination, arrangement and relative location of the parts as will appear from the following description.

Referring to the drawings:

Figure 1 is a side elevational view of a strip employing the principles of my invention:

Figure 2 is a top plan view of a strip of similar construction showing, however, only two projecting members:

Figure 3 is a cross-sectional view taken on the line 3-3 of Figure 2:

Figure 4 is a cross-sectional view taken on the line 4-4 of Figure 2:

Figure 5 is an enlarged side elevational detailed view of a strip showing a modified projecting tab:

Figure 6 is a cross-sectional view on the line 6-6 of Figure 5:

Figure 7 is a side elevational view of a modified form of a strip:

Figure 8 is a top plan view of this strip, and

Figure 9 is a detailed plan view of two adjacent floor sections showing the manner in which the strip is mounted therebetween.

It is now common practice in the construction of modern office and residential buildings, to provide a flooring composed of various composition material broken up into a series of squares or blocks and arranged to permit relative movement between the various blocks to accommodate the floor to changes in temperature. It has been common to place between the adjoining edges of the blocks comprising the floor protecting strips which will permit relative movement of the various blocks with respect to each other, also prevent chipping of the blocks at the edges and cracking thereof. The types of strips ordinarily used at the present time either move away from the edges of the blocks so as to prevent protection thereof, or become bent and distorted due to temperature changes which cause creeping of the composition flooring. These effects are also due to settling of the building.

I have, by means of my invention, provided a protecting strip which always remains straight and which while permitting relative movement between the blocks comprising the floor provide means for protecting the edges thereof and, at the same time, maintaining the strip undistorted.

Referring to the drawings, in Figures 1 to 4, I have shown one modification of the invention. The strip comprises a main body member of metal or other suitable material of the proper thickness from which has been struck up the tabs or projecting members 2 and 3. The tabs 2 all project from one side of the strip, while the tabs 3 all project from the opposite side of the strip. The members or tabs 2 consist of plane members with a curved edge as shown in Figure 2. The projecting members or tabs 3, while of the same

outline, are cupped or dished as at 4. In Figures 5 and 6 the strip is shown at 5 having the tabs 6 which correspond to the tabs 3 of the other form of the invention, but in this case the tabs 6 are provided with a series of holes 7. In Figures 7 and 8 the strip is shown at 8 having the plane up struck tabs 9 all projecting from the same side of the strip and alternating with the tabs 10 which are struck up from the opposite side of the strip. The tabs 10 are split at their ends to provide the short arms 11 projecting at right angles to the arm 10 as is shown in these figures.

In each of these forms of the invention a series of plane tabs as at 2 and 9 project from one side of the strip and alternate with a series of tabs projecting from the other side of the strip which may have a variety of forms of which three have been indicated in the present drawings. It is, of course, evident that many changes in the details of construction and relative arrangement of parts will readily occur to those skilled in the art and I do not, therefore, desire to be limited to the particular form or relative arrangement of tabs or securing members on the strips.

I have shown in Figure 9 the way the strip co-operates with the various flooring sections. At 5 are shown two adjoining blocks between which is mounted the strip indicated at 1. At 30 which is mounted the strip indicated at 1. The face of the strip having the cupped tabs 3 is rigidly secured against the edge of the lower block 5 by reason of the fact that the composition is packed around the cupped tabs to firmly embed them therein. When the form of strip shown in Figure 6 is used the tabs 6 having the holes 7 therein are firmly embedded in the flooring by reason of these holes. In the form shown in Figures 40 7 and 8 the projecting arms are firmly embedded in the composition flooring by reason of the bent arms 11. The tabs 2, while they are embedded in the upper block, may readily move transversely with respect thereto when any relative movement between the blocks occur. In view of the shape of the tabs 2 it is evident that they are not firmly secured in the flooring composition and will readily move with respect to the block and be guided thereby.

It will be apparent from the foregoing description that a strip constructed in accordance with the principles of my invention will always remain straight while protecting the edges of the blocks forming the floor as they move with respect to each other due to heat changes.

I am, of course, aware that many changes in the details of construction will occur to those skilled in the art and I do not, therefore, desire to be limited except as required by the appended claim.

What I seek to secure by United States Letters Patent is:

65 In a device of the type described the com-

bination with a composition flooring having a plurality of sections, of a protecting strip between the adjoining faces of adjacent sections and cupped means on one side of said strip for securing it to one of said faces and additional flat means on the other side of said strip for at the same time permitting relative guided movement of said strip with respect to the other face.

In testimony whereof I have hereunto set my hand on this 1st day of March, A. D. 1927.

FREDERICK A. KAPPELMANN.
